(57) **CLAIM**

The ornamental design for a load control device, as shown and described.

DESCRIPTION

This application is also related to U.S. patent application Ser. No. 29/449,250, filed on Mar. 14, 2013 and entitled “Load Control Device,” U.S. patent application Ser. No. 29/449,237, filed on Mar. 14, 2013 and entitled “Load Control Device,” U.S. patent application Ser. No. 29/449,242, filed on Mar. 14, 2013 and entitled “Load Control Device,” U.S. patent application Ser. No. 29/449,257, filed on Mar. 14, 2013 and entitled “Load Control Device,” and U.S. patent application Ser. No. 29/449,263, filed on Mar. 14, 2013 and entitled “Load Control Device.”

FIG. 1 is a perspective view of an embodiment of a load control device embodying our new design;

FIG. 2 is a front view of the load control device of FIG. 1; FIG. 3 is a first side view of the load control device of FIG. 1;

FIG. 4 is a second side view of the load control device of FIG. 1;

FIG. 5 is a top view of the load control device of FIG. 1; and, FIG. 6 is a bottom view of the load control device of FIG. 1.

The broken lines in the drawings are included for the purpose of illustrating an environment of the article and
